BUCKLE

Albert P. J. Voigt and Lawrence M. Still, Galveston, Tex., assignors to Galveston Buckle Company, a corporation

Original application March 29, 1932, Serial No. 601,738. Divided and this application July 27, 1936, Serial No. 92,806

3 Claims. (Cl. 24—26)

This is a division of application Serial No. 601,738, filed March 29, 1932.

The invention relates to buckles which are particularly adapted for connecting ties or bands in 5 confining cotton or other similar materials.

In forming bales of material, such as cotton, it is essential that the material be confined by suitable ties which can be quickly applied and which will permanently confine the material 10 even when it has been compressed under heavy pressure. In order to hold the material compressed under heavy pressures, as in the case of cotton baled for shipment to considerable distances, it is necessary to have ties and buckles 15 of great strength. With this in mind, the present invention has been concerned with a view of providing a buckle of great strength and which is suitable for holding the ends of the bale ties on high density bales.

It is an object of this invention to provide a buckle which is economical to make and which is 20 strong.

Another object of the invention is the production of a safety buckle as distinguished from 25 the usual and well known type of C buckle.

Another object is to provide a buckle that lends 30 itself to automatic and continuous production from lengths of strip stock.

Still another object is the provision of a buckle 35 in which the hook member extends laterally from the plane of the buckle and of which the central portion comprises a sharp bend to peripherally receive the adjacent tie-engaging member when strain is placed upon a tie placed thereon.

Other and further objects will be apparent 40 from the drawing which illustrates the process of fabrication of the article and the article per se.

In the drawing, Fig. 1 illustrates the position 45 of a section of wire rod in clamped position ready for the forming operation.

Fig. 2 shows the position of the dies at the end of the preliminary forming step.

Fig. 3 shows the preliminary step in the formation of the buckle hook.

Fig. 4 shows the final die operation in the formation of the hook.

Figs. 5, 6 and 7, respectively, show a plan view, side elevation and end view of the completed 50 article.

In Fig. 1 the numeral 1 indicates a section of wire cut by any suitable means and ready for the preliminary forming operation. The next step after the wire has been cut is the gripping 55 of the wire so that it may be bent. To accom-

plish this, a buckle forming die or support 2 is provided. This die is of such suitable configuration that when the wire 1 is wrapped thereabout a quadrangular-shaped open loop is provided. In order that such wrapping of the wire about 5 the die 2 may be effected it is necessary that the wire be held securely in place on the die. This is effected through the instrumentality of a vise member 3 which clamps the rod against the die member 2. In view of the fact that excessive 10 pressure will be necessary to thus hold the wire a second member 6 is provided adjacent the vise member 3 to prevent upward movement of the end of the wire 1.

A second die member 4 is provided to wrap the 15 wire about the die 2. This die member is suitably mounted, as is clearly shown in the application of which this is a division, to provide the desired wrapping action.

Fig. 2 illustrates the procedure in the forming 20 of the quadrangular-shaped open loop of the buckle. In that figure the die member 4 is shown to have passed, as indicated by the dotted arrows, about the die member 2, thus wrapping the wire 1 to the configuration there shown.

The next step in the formation of the buckle 25 after the end has been wrapped to the position shown in Fig. 2 is the formation of a safety catch on the end 7. This operation is shown in Figs. 3 and 4 wherein the end 7 is bent laterally to 30 form the hook 9. The end of the wire must be supported in order to accomplish this bending movement and the buckle must be given its final set by moving the end 8 into proper position with respect to the side 10 and the end 11. To accom-

plish this a hook-forming die 12 is provided. This die is shown in cross section in Figs. 3 and 35 4 and is provided with a groove 13 on one side to engage the end 8 of the wire 1. The preformed quadrangular-shaped loop is placed upon the 40 die 12 and is held thereon by vise member 14. The preliminary forming step for the hook is then produced by the die member 15 moving 45 downwardly to bend the end 7 over the die 12. It is understood that forming die 12 must be of sturdy construction and must withstand the pressure of the dies which bend the wire into the formation of the safety hook and which must maintain the final position so that the hook will have the proper set. To assist in maintaining 50 this condition a support 16 may be provided for the die 12.

The downward movement of the die 15 will form only a portion of the safety hook. The next step to complete the hook is illustrated in 55

Fig. 4 and comprises a further die member 17 which moves in a horizontal direction to further bend the end 7 about the die 12, thus completing the hook portion of the buckle.

5 The surface 18 of the hook forming die is designed with such a configuration that it will form a more or less gradual curve in the wire at 19 and with a sharp bend at 20. The hook is so formed in order that the end 8 will move into 10 the sharp bend at 20. The gradually curved portion 19 of the hook will not straighten under the tension placed thereon and hence opening of the hook will not occur. This gradually curved portion provides a slightly opened hook 15 that will, under all circumstances, effectively receive the end portion 8 of the buckle when strain is placed upon the tie engaging members 10, 10' and will guide said end portion 8 into the sharp bend 20 which is of such configuration as 20 to receive said end portion in peripheral contact.

With the bend 20 positioned out of alignment with the end of 11', but in the line of movement of the end 8, when strain is placed on side element 10', the thrust on the side 10' is absorbed by the bend 20 which is in direct alignment with that thrust. Other types of safety buckles have been devised heretofore wherein the center of the bend was in alignment with end 11' of the 30 buckle but these were found unsatisfactory due to the fact that less gradual curving of the portion of the hook adjacent the throat thereof caused straightening of the hook when subjected to the stresses occurring in normal use thereof. 35 Further, previously devised buckles do not permit ease in applying bale tie to members 10 and 10' as with the buckle herein described. It is thus to be seen that a buckle has been perfected that is strong and economical to make 40 and which will effectively serve the purpose for

which designed. While a specific embodiment thereof has been described, it is not desired to be limited thereby but only insofar as disclosed by the prior art and claims appended hereto.

What we claim as new is:

1. A bale tie buckle comprising a wire bent to a four-sided figure having two sides and two ends, a substantially right angle bend at one corner so that one end and one side lie in the same plane, a hook formed in the wire of said end, said hook extending in a plane transversely of the side and end, a hump in said end to throw said hook out of the plane of said side and end, a substantial right angle bend at a second corner to form the second end in substantially the same plane as said first side and end, and an acute angle bend in the wire at a third corner to form a second side, the wire of said second side extending across said first end inside of said hook. 5

2. A rectangular wire bale tie buckle having a first side and a second side and a first end and a second end, substantially right angle bends at the corners joining said ends with said first side, a hook on said first side, a hump in said first side to position said hook laterally out of the general plane of the buckle, an acute angle bend at the corner joining said second end and second side, said second side being of a length to cross over said first end within said hook 15 and adjacent said hump. 20

3. A rectangular bale tie buckle comprising an end, a hump in said end, a hook on said end, a side bent inwardly and laterally to cross said end within said hump and hook and spaced from both said hook and hump so that the bale tie 35 may be readily passed thereover.
